WATER TAP FILTER

Samuel Lieberman, Newton, Mass., assignor to Eugene Shannon, Dedham, Mass.

Filed Dec. 1, 1972, Ser. No. 311,243

Term of patent 14 years

Int. Cl. D23—01

U.S. Cl. D23—4

FIG. 2

FIG. 3

FIG. 1 is a side elevational view of a water tap filter embodying my new design;

FIG. 2 is a top plan view thereof; and

FIG. 3 is a bottom plan view thereof.

I claim:

The ornamental design for a water tap filter, as shown.
